US0D1086016S

(12) **United States Design Patent** (10) **Patent No.:** **US D1,086,016 S**
(45) **Date of Patent:** **** Jul. 29, 2025**

(54) **RESONATOR DEVICE**

- (71) Applicant: **SimpliSafe, Inc.**, Boston, MA (US)
(72) Inventor: **Scott Thorne**, Boston, MA (US)
(73) Assignee: **SimpliSafe Inc.**, Boston, MA (US)
(**) Term: **15 Years**
(21) Appl. No.: **29/912,445**
(22) Filed: **Sep. 19, 2023**

Related U.S. Application Data

- (63) Continuation-in-part of application No. 29/868,042, filed on Nov. 17, 2022.

CLAIM

The ornamental design for a resonator device as shown and described.

DESCRIPTION

FIG. 1 is a perspective view showing a first embodiment of a resonator device as seen from the top, front, and first side; FIG. 2 is a front elevation view thereof; FIG. 3 is a back elevation view thereof; FIG. 4 is a first side elevation view thereof; FIG. 5 is a second side elevation view thereof; FIG. 6 is a top plan view thereof; FIG. 7 is a bottom plan view thereof; FIG. 8 is a perspective view showing a second embodiment of a resonator device as seen from the top, front, and first side; FIG. 9 is a front elevation view thereof; FIG. 10 is a back elevation view thereof; FIG. 11 is a first side elevation view thereof; FIG. 12 is a second side elevation view thereof; FIG. 13 is a top plan view thereof; and, FIG. 14 is a bottom plan view thereof.

The broken lines shown in the drawings represent unclaimed subject matter and form no part of the claimed design.

1 Claim, 10 Drawing Sheets
